UNITED STATES PATENT OFFICE.

JOHN WILSON, OF WILMOT, MICHIGAN.

FIRE-ALARM APPARATUS.

1,356,104.

Specification of Letters Patent.

Patented Oct. 19, 1920.

Application filed January 23, 1920. Serial No. 353,422.

To all whom it may concern:

Be it known that I, JOHN WILSON, a citizen of the United States of America, residing at Wilmot, in the county of Tuscola and

5 State of Michigan, have invented certain new and useful Improvements in Fire-Alarm Apparatus, of which the following is a specification, reference being had there-
in to the accompanying drawings.

10 This invention relates to a fire alarm apparatus and has for its principal object the provision of efficient means carried by the roof of a building contiguous to the chimney for sounding an alarm when the building is
15 on fire near or adjacent to the chimney.

With these and other objects in view this invention consists of certain novel combinations, constructions, and arrangements of parts as will be hereinafter fully described
20 and claimed.

In the drawings:

Figure 1 is a sectional view of a building, showing in side elevation my apparatus in place thereon.

25 Fig. 2 is a fragmentary perspective view of a building, showing particularly the positioning of the upper portion of my apparatus on the roof contiguous to the chimney.

Fig. 3 is a diagrammatic perspective view
30 of my apparatus showing particularly the alarm.

Fig. 4 is a vertical sectional view of one of the sleeves carried by the roof of the building.

35 Fig. 5 is a fragmentary side view of one of the bars or triggers showing the wood eyelet therein.

Referring to the drawings by numerals 1 designates a bell that I preferably attach
40 to the chimney 2 by means of a plate 2^a. Coöoperating with the bell 1 is a striker 3 of the clapper device A, that is operated by a coiled spring device formed in the usual manner; this coiled spring device is
45 provided with a frame 4 and ratchet 5, and engaging ratchet 5 is the pawl or dog device 6.

This pawl device comprises weighted bar 7, which bar 7 is engaged near its forward end by an angle extension 8 of coiled spring 9, which coiled spring 9 is fastened around the pivot pin 10 of the pawl device 6. This spring 9 holds the toothed end 11 of the bar 7 normally in engagement with the teeth of the ratchet wheel 5, preventing the alarm from sounding by reason of the gears

being held against the action of the coiled spring of the clapper device, which coiled spring and gears together with the clapper 3 is of any ordinary spring actuated bell 60 sounding device. The inner end of the pin or bar 10 is journaled in a plate 10^a (Fig. 3) fastened to the primary plate 2^a that is normally attached to the chimney 2.

The inner end 12 of bar or pawl 7 is 65 engaged by a plurality of bars or fingers 13, which bars or fingers 13 are pivotally mounted upon a substantially U-shaped bracket 14 that is secured to the chimney plate 2^a. On the bracket 14 are positioned 70 coiled springs 15 that exert a downward pressure at their outer angle ends 16 upon the auxiliary bars 13. Near the outer end of each bar 13 is formed an enlarged portion having an aperture and in the aperture, at 17, is positioned the cables or cords 18, which cables or cords 18 are formed of any inflammable or fusible material, so as to be more quickly severed by a flame, when a house or dwelling is on fire.

80 As seen more particularly in the diagram shown in Fig. 3, the cords 18 may lead to several chimneys as B, or the cords 18 may lead to the furnace C in the basement of a dwelling or building; the same function 85 being produced in any case, whether the cord leads to a chimney or near a furnace and hence it will only be necessary to describe the connection and operation of one set of cords which I have particularly shown 90 in Figs. 1 and 2 of the drawings.

It will be understood that if any one of the cords or cables 18 is severed, this severance will release the auxiliary bar or trigger 13, causing the bar or trigger, through 95 the action of the spring 15 thereof, to move downwardly, pressing strongly upon the end 12 of the pawl 7, disengaging the tooth 11 thereof from the ratchet wheel 5, thereby sounding the alarm through the action of 100 the clapper device upon the bell 1.

To each of the cords or cables 18, running to a chimney, at its upper end is attached a pulley 19 around which the intermediate cord or cable 20 passes. To the 105 upper ends of the intermediate cord or cable 20 are secured the intermediate pulleys 21. Passing around each of pulleys 21 are roof connecting cords or cables 22.

The cords or cables 22 pass over guide 110 pulleys 23, Fig. 1, fastened to the side of the chimney 2 and thence they pass over

corner-pulleys 24 and through sleeves 25 carried in the roof 26 of the building, these sleeves 25 being arranged close to the chimney so that if the roof catches on fire near 5 the chimney a cord or cords will be severed by burning of same, thereby permitting at least one of the pulleys 21 to drop consequently permitting pulley 19 and cord 18 to drop too, releasing spring-pressed bar or trigger 13, whereby it will press down upon end 12 of bar 7 releasing the clapper device and thereby resulting in the sounding of the 10 alarm.

Each sleeve 25 is provided with a pulley 15 27 in its upper end over which a roof connecting cord or cable 22 passes. The outer ends of these roof connecting cords 22 are fastened, as at 28, to different parts of the 20 roof.

It will be obvious that these roof connecting cords or cables 22 can be extended a greater or a less distance from the chimney, the extending of the cords 22 to the extreme edge of the roof falling within the 25 scope of this invention.

It will be noted, upon referring to Figs. 1 and 2 that the greater portion of the pulleys and the rigging of the apparatus is in the attic D of the house or dwelling. 30 Further, the operation of the signaling device is just the same with respect to the inflammable or fusible cord 18 leading to the furnace C; suitable pulley arrangements can be placed around the furnace just 35 as the pulleys shown in Figs. 1 and 2 are placed around the chimney, and the severance of the cord or cable 18 will have the same effect upon the signaling device as the severance of the cords or cables 18 leading 40 to the chimneys.

In Fig. 5 I have shown an enlarged view of one of the bars or triggers, showing a wood eyelet 13^a through which the cable 18 extends; all of the bars or triggers 13 have 45 this wood eyelet 13^a. These wood eyelets 13^a do not cut the cords or cables 18, thereby making the connections more lasting.

It is to be understood that I reserve the right to make such alterations and changes 50 in the construction of my apparatus as shall fairly fall within the scope of the appended claims.

What I claim is:

1. In an apparatus of the class described, 55 the combination with a plate, a spring actuated clapper and bell device carried by said plate, of a spring held pawl coöperating

with said clapper and bell device for normally preventing the same sounding an alarm, said pawl provided with a comparatively long rear end, a stationary bracket secured to said plate, a plurality of triggers pivotally mounted upon said bracket, springs upon said bracket and engaging said triggers and exerting a downward pressure thereon, each trigger engaging the rear end of said pawl, and inflammable or fusible means connected to the trigger near its outer end and normally holding the trigger so that the spring coöperating therewith will not force the same downwardly against the rear end of the pawl sufficiently to disengage the pawl from the spring and bell device. 60 65 70

2. In an apparatus of the class described, 75 the combination of a plate, a signaling device provided with a pawl carried by said plate, a stationary bracket secured to said plate, a trigger pivotally mounted upon said bracket and engaging said pawl, means on said bracket and engaging said trigger for forcing the same downwardly when said trigger is released, said trigger provided near its outer end with a transversely-positioned horizontal wood eyelet, and means 80 85 connected to the trigger in the wood eyelet for normally preventing the trigger from swinging downwardly upon the bracket and releasing the pawl. 90

3. In an apparatus of the class described, 90 the combination of a plate, a signaling device provided with a pawl carried by said plate, a stationary bracket positioned at right angles to the plate and having its ends secured thereto, a plurality of triggers pivotally mounted at their inner ends upon said bracket between its ends, the outer ends of all of said triggers resting upon the top of said pawl, coil springs on said bracket between said triggers, each coil spring having its outer end pressing down upon a trigger between its ends and having its inner end engaging the plate, each trigger near its outer end provided with a transversely-positioned horizontal wood eyelet extending therethrough, and means threaded through the wood eyelets of the triggers for normally preventing the triggers from swinging downward upon the bracket and releasing the pawl. 95 100 105 110

In testimony whereof I hereunto affix my signature.

JOHN WILSON.
